BREAST PAD AND THE LIKE

Elsie L. Martin, Drexel Hill, Pa.

Application December 1, 1936, Serial No. 113,737

7 Claims. (Cl. 2—267)

My invention relates to breast pads and the like, and to a novel combination of such a pad with a garment or device such as a band, brassière, girdle, foundation, corset, etc. My novel pad can be 5 made to afford a perfect substitute for a natural breast (for surgical cases), or can be adapted to remedy deficiencies of bust development. Not only can it afford the appearance of a natural bust when worn by a normally dressed woman, or 10 even when worn under a bathing suit, but it can also simulate the natural breast to the casual touch so as to escape detection. It can be made light and comfortable to wear, self-ventilating and highly sanitary, and easy to wash, renovate, 15 or even disinfect when necessary. It is easy and inexpensive to make, and can be quickly and easily adapted to the particular requirements of any individual wearer, so as to simulate her normal or proper breast perfectly. It can be worn with an 20 evening gown as well as with any other type of dress.

A great variety of breast-pads have heretofore been designed: some consisting of pneumatic cells; some of stiff and hollow construction; some of flexible fabric stuffed with a fibrous filling like curled hair or cotton batting; and some modelled of elastic material such as sponge rubber. All, however, have been subject to certain principal drawbacks: viz, their construction was of such 30 character as to give each pad a substantially fixed form, which could not readily be modified to simulate the actual or normal bust of an individual wearer; and at best the prior pads had only the elasticity of rubber, without the plasticity characteristic of a normal human breast. Also many 35 such pads have been either so impervious to air as to prevent proper ventilation through them, or very absorbent of perspiration and body odors, while at the same time difficult or impossible to cleanse, renovate, or disinfect. Many, too, could not be worn for bathing or swimming without being ruined or at least losing their shape and elasticity temporarily, so as to betray their artificial character.

45 I overcome the chief drawbacks of prior devices by making my pad plastic substantially like a normal breast, and also elastically deformable like a breast. Using a pad that is plastic, I am able to adapt its form very easily to simulate the 50 proper or normal bust of any woman who wears it, by associating the pad with a garment band, or the like that conforms to such wearer's proper, normal bust. For present styles in women's wear, such garment or device will usually correspond to a 55 brassière such as now generally used; either a

separate brassière, or one forming part of a girdle, foundation, or corset, etc. Associated with such a garment or device that supports, confines, or molds the bust, my plastic breast-pad is molded and held in place by it very much as the natural or 5 normal breast of the wearer is or would be.

Preferably, my pad is detachably secured to the brassière or the like, as by pins, hooks and eyes, snap fasteners such as used on gloves, or even by stitching.

10 While my novel breast-pad is thus easily brought into the form of a wearer's normal or proper bust, it may, of course, be desirable to make such pads in a variety of sizes corresponding to the volume of breast appropriate to different torsos, and in "rights" and "lefts". The pad may be 15 of any material and construction that will give the proper plasticity and elasticity; but I prefer a flexible envelope containing loose particles or shreds of filling material, since this lends itself 20 to both lightness and permeability of the pad. While such loose filler particles suffice to give plasticity and a certain elasticity, yet somewhat greater elasticity may be obtained by using particles or small pieces of elastic material. A filling 25 of small pieces or shreds of elastic sponge combines lightness, elasticity, and permeability to air in a high degree,—especially natural sponge, or elastic sponge-rubber such as used for bath sponges.

30 A property that is very desirable for the filling used in my pad is illustrated by the behavior of shredded sponge rubber such as may readily be made by cutting small pieces off a rubber bath sponge with a pair of scissors. Besides being individually elastic and shifting relative to one another with a good deal of freedom, such small pieces of rubber have sufficient friction with one another to "stick" and resist slipping over one another when any firm pressure is exerted on a mass of such pieces. Thus the pad in use exhibits the elastic firmness of a breast in a brassière.

35 The envelope of my pad may be of any fabric or texture that will retain the particles of filling and yield with them. A permeable, woven or knitted fabric offers the advantages of ventilation and of ease in washing the pad; while an impermeable fabric like oil silk, sheet rubber, cellophane, etc. excludes moisture and odors from 40 the filling.

45 Other features and advantages of my invention will appear from the following description of a species or form of embodiment, and from the drawing. So far as novel over the art, indeed, all 50 55

the features and combinations herein illustrated or described are of my invention.

In the drawing, Fig. 1 is a perspective front view of a pad conveniently embodying my invention; Fig. 2 is a rear elevation; and Fig. 3 is a vertical mid-section.

Figs. 4 and 5 are plan views of the two halves of the envelope of the pad.

Fig. 6 is a perspective front view of an elastic 10 nipple forming part of the pad as illustrated; and Fig. 7 is a fragmentary view of some of the filling material.

Fig. 8 is a partial perspective view of a person 15 wearing the pad in a brassière; Fig. 9 is a corresponding side view, with the brassière partly broken away; and Fig. 10 is a partial back view, showing certain features of the brassière.

As shown in Figs. 1, 2, and 3, my pad P is of a 20 pointed-oval outline and of considerable convexity in front, while its back may be nearly flat. Its envelope 10, which may be made of fabric such as glove-silk or satin, comprises a front piece 11 and a back piece 12, with their edges coincident and stitched together as indicated at 13 25 in Fig. 3. As best shown in Figs. 1 and 3, the front 11 is not intrinsically flat, but convex, while the back 12 may be substantially flat except as modified by conformity to the breastless (or 30 flat-breasted) torso of the wearer. At its apex or point of greatest forward projection (when worn), the pad P may have an elastic nipple projection 14, to simulate the natural nipple of the wearer under her clothing. In Fig. 3, the envelope 10 is shown filled with shreds, flakes, or 35 chips 15 of elastic sponge.

One way of giving the front 11 the desired convexity is to gather and sew its lower mid-portion (below its apex, where the nipple 14 is attached) into a plurality of knife-pleats or tucks, as illustrated in Figs. 1 and 4. Figs. 1 and 4 show two such tucks. Being naturally stiffer than the single ply fabric, these folds or tucks also serve as a stitched-in stiffening uplift to keep the pad in shape and prevent any tendency to sagging. In Fig. 4, the lines of fold or crease of the fabric for each tuck are shown by heavy dotted lines A and B, while the places where the creases will lie against the unfolded fabric are indicated by the light dotted lines a and b. The lines of 45 stitching 17 to secure the folds flat on the unfolded fabric may follow the (outer) coincident lines Aa, Aa without following the (inner) coincident lines Bb, Bb: e. g., the lines of stitches may be in a series of nested Vs, as shown in 50 Fig. 1.

The back 12 may consist of a single piece of fabric as shown in Fig. 5, or of two separate pieces 18 and 19 overlapping considerably as indicated at 20 and 21 in Fig. 2. The edge of the 60 overlapping piece 18 may be widely turned under as indicated at 22.

During manufacture, the back pieces 18 and 65 19 may be basted together in their relation as shown in Fig. 2 until their edges have been sewed to the front piece 11, along seam 13. Preferably, this is done with the sides of the front 11 and back 12 that are outermost in Figs. 1-3 toward one another. Then the basting stitches may be removed, and the whole envelope turned inside 70 out, so that the edges of front 11 and back 12 are at the inside, as shown in Fig. 3. The opening at 20 between the pieces 18, 19 may thereafter be used for introducing the filling 15 into the envelope, and then basted or sewed up again as indicated at 22. This may preferably be done

with stitches easy to remove; so that the pad can readily be reopened if occasion afterward arises for changing the amount of filling in the pad P, or for replacing it with different or fresh filling. As shown in Figs. 1 and 2, the envelope 10 has 5 pairs of eyelets 23 worked or secured in its upper edge, at its middle and at both ends or corners; these open through both the front 11 and the back 12. In manufacture, patterns of substantially the outlines shown in Figs. 4 and 5 may 10 conveniently be used for cutting out the fronts 11 and backs 12. If preferred, the back 12 may originally be in one piece, with a flat pleat formed by folding along the lines 20, 21; and after the front 11 and back 12 have been sewed together at 13, the opening at 20 may be formed by cutting along the line 21, preparatory to turning the envelope inside out as above mentioned.

As shown in Fig. 6, the nipple 14 may consist of hollow elastic vulcanized rubber, like a rubber 20 finger-cap, and may be provided with holes 24 through its margin at its base (three being shown) for stitches 25 to secure it to the envelope front 11. When the pad is worn under a brassière, as hereinafter described, the nipple 14 will 25 be flattened according to the tightness of the brassière, just like a natural nipple.

Fig. 7 shows the filler shreds, flakes, or chips 15 of sponge rubber, such as may be made by cutting pieces off a rubber bath-sponge with a pair 30 of scissors. The pad P is preferably just about filled (but not at all stuffed) with these, so as to exhibit a certain plasticity when handled, or under any force tending to deform it. The pieces 15 may be rather flat.

Figs. 8 and 9 show the pad P of Figs. 1, 2, and 3 as worn under a brassière B of ordinary and very simple design and construction. The particular brassière illustrated comprises breast pieces 27, 27 mainly of rather inelastic glove silk or the like, but with diamond-shaped "inset" top portions 28, 28 of lace and/or net. These breast pieces 27, 27 are supported by narrow shoulder straps of inelastic ribbon 29, 29 attached to the upper points or angles 30, 30 of the diamond portions 28, 28. These parts 28, 28 are cut with their lower angles more acute than those originally existing between the upper edges of the glove-silk to which the lower edges of said pieces 28, 28 are seamed at 31, 31, so that the breast pieces 40 27, 27 bag forward as pockets adapted to hold, support, and even mold the natural (or normal) breasts of the wearer. The breast pieces 27, 27 narrow from the points 30, 30 to their junction (at seam 32), by reduction along both their upper 45 and their lower edges, and also narrow in like manner around under the arms of the wearer, where they are attached (by seams 33, 33) to gradually narrowing strips 35, 35 (of inelastic glove-silk or the like such as above mentioned) 50 which extend around the sides and back of the wearer, where the rear ends of the shoulder straps 29, 29 are attached to them. The edges of the parts 27, 28, 35 may be bound with tape or otherwise suitably finished. (Fig. 10). The shoulder- 55 straps 29, 29 may preferably be provided with suitable means of length adjustment, such as rings 36 and friction-buckles 37, as shown in Figs. 8 and 9. The rear ends of the strips 35, 35 60 may be interconnected and detachably fastened together in any suitable manner,—as by a short length of rubber-elastic tape 38 sewed to one strip 35 and having an eye 40 for engagement with a hook 41 on the end of the other strip 35.

As shown in Figs. 8 and 9, my pad P is being 75

worn as a substitute for a removed left breast, being held in the breast piece 27 of the brassière B and molded thereby into a sufficiently close resemblance to the natural form of the missing breast. As shown, the upper edge of pad P is secured to the upper portion of breast-piece 27 at three suitably-located points, as by small safety-pins 44 stuck through the brassière fabric and taking through the above described eyes in the pad P. One good way of locating and securing the pad P in the brassière B is to put on the brassière with the pad loose therein, then bring the pad into just the right position and pin it there temporarily with ordinary pins or safety-pins (not shown), then take off the brassière and pin the pad in place more permanently with the small safety-pins 44,—inserted from the inside of the pad so as not to be noticeable in the brassière under a thin dress,—and finally remove the first-mentioned pins.

It will readily be appreciated that a brassière B and pad P may be worn under a bathing suit as readily as under any ordinary dress or evening gown, since its elasticity is not affected by wetting, and it is in nowise injured by water. The pad P can be washed with soap and water and squeezed out, and will dry easily. It can also be washed in an antiseptic, germicidal, or deodorant solution, if this should be desirable for any reason.

I claim as my invention and desire to secure by Letters Patent of the United States:

1. The combination with a brassière fitted to the body of a wearer and conformable to her normal bust, of a breast pad in a breast portion of a said brassière filled with loose compressively elastic shreds so that the pad is plastically

molded by the brassière, when worn, into substantially the form of the wearer's normal breast, and is also plastically and elastically deformable, substantially like a normal breast.

2. The combination with a brassière fitted to the body of a wearer and conformable to her normal bust, of a plastic and elastic pad in a breast portion of said brassière filled with shreds of elastic sponge so as to be plastically molded by the brassière, when worn, into substantially the form of the wearer's normal breast.

3. A breast pad of the character described, comprising a flexible envelope with a filling of loose shreds rendering the pad when worn plastically moldable and deformable, substantially like a normal breast.

4. A breast pad of the character described, comprising a flexible envelope with a filling of loose compressively elastic particles.

5. A breast pad of the character described, comprising a flexible envelope filled with shreds of elastic sponge, so that when worn the pad is plastically and elastically moldable and deformable substantially like a normal breast.

6. A breast pad of the character described, comprising a flexible envelope filled with small pieces of elastic sponge rubber.

7. A breast pad of the character described, convex in front, and comprising a flexible envelope with a filling of loose shreds rendering the pad when worn plastically moldable and deformable substantially like a normal breast, and having a stiffening uplift stitched into its front envelope wall below its point of greatest forward projection.

ELSIE L. MARTIN.
